A. A. BACKHAUS AND F. B. ARENTZ.
APPARATUS FOR MAKING ALDEHYDES AND SEPARATING THE SAME FROM THE OTHER PRODUCTS FORMED.
APPLICATION FILED JUNE 24, 1918.

1,426,449.

Patented Aug. 22, 1922.

UNITED STATES PATENT OFFICE.

ARTHUR A. BACKHAUS, OF BALTIMORE, AND FRED B. ARENTZ, OF CURTIS BAY, MARYLAND, ASSIGNORS TO U. S. INDUSTRIAL ALCOHOL CO., A CORPORATION OF WEST VIRGINIA.

APPARATUS FOR MAKING ALDEHYDES AND SEPARATING THE SAME FROM THE OTHER PRODUCTS FORMED.

1,426,449.

Specification of Letters Patent. Patented Aug. 22, 1922.

Application filed June 24, 1918. Serial No. 241,651.

To all whom it may concern:

Be it known that we, ARTHUR A. BACKHAUS, of Baltimore, in the State of Maryland, and FRED B. ARENTZ, of Curtis Bay, in the county of Anne Arundel, and in the State of Maryland, have invented a certain new and useful Improvement in Apparatus for making Aldehydes and Separating the same from the Other Products Formed, and do hereby declare that the following is a full, clear, and exact description thereof.

Our invention relates particularly to an apparatus for producing aldehydes, but it has reference particularly to apparatus for the production of acetaldehyde.

The object of our invention is to provide an apparatus by means of which aldehydes, and particularly acetaldehyde, may be readily formed from the corresponding alcohol.

A further object is the operation of said apparatus by means of a catalyzer.

The object of our invention is especially to provide an apparatus to recover the aldehyde and separate it from the other products of the process in an advantageous manner.

Further objects of our invention will appear from the detailed description thereof contained hereinafter.

While our invention is capable of embodiment in many different forms, for the purpose of illustration we shall describe only one form of apparatus made in accordance with our invention in the accompanying drawings, in which

The figure is a diagrammatic representation, partly in section, of an apparatus which may be used in carrying out our invention.

In the drawing, we have shown an alcohol still 1, adapted to be heated by means of a steam jacket 2, having a vapor outlet pipe 3, which passes through a preheater 4, adapted to be heated in any suitable way, as for example by an oil jacket 4^a, having inlet and outlet pipes 4^b and 4^c. The tube 3 is connected to a catalyzer 5, which is comprised of a copper tube 6, carrying a quantity of granular porous material 6^a, such for example as pumice stone, unglazed porcelain, charcoal or terra cotta, carrying

throughout the same particles of a finely divided catalyzer metal such for example as copper, nickel, chromium or iron, which may be deposited therein by any suitable means, but preferably in such a manner as to involve the reduction of an oxide of the metal by a current of hydrogen, as for example in accordance with the process of making catalyzers set forth in application, Serial Number, 240221, filed June 15, 1918, by Arthur A. Backhaus.

Said catalyzer 5 is provided with any suitable heating means, but may, for example, be provided for this purpose with a heating jacket 7, having inlet and outlet pipes 8 and 9, respectively, for supplying a current of highly heated oil thereto. A tube 10 leads from the upper portion of the catalyzer 5 to a condenser 11, which is provided with the usual inlet and outlet pipes for cooling water 12 and 13, and which is adapted to condense the alcohol from the vapors which pass out of the catalyzer 5. The condensed alcohol is caught in a cylindrical receiver 14 and may be drawn off by valved pipe 15, while the uncondensed gases, comprising acetaldehyde and hydrogen, pass out by a pipe 16, which may, if desired, contain a compressor 16^a, and thence to a scrubbing tower or column 17. The vapors in the tower 17 pass through a series of liquid sealed pans 18, constructed in the same manner in which scrubbing towers or columns are ordinarily made, in which pans a current of absorbing liquid is caused to flow in the opposite direction from an inlet pipe 19 located at the top of the tower. The absorbing liquid may be water or alcohol, but said liquid is preferably comprised of acetic acid, the most preferred form of which for this purpose is glacial acetic acid, in which the aldehyde formed is very soluble. In this way an acetic acid containing 50% of acetaldehyde may be obtained and will flow out of the tower 17 by means of an outlet pipe 20, and thence into a receiver 21, from which it may be drawn off by an outlet pipe 22. The hydrogen passes out of the tower 17 by means of a pipe 23, and may be collected in any suitable manner.

In the operation of our apparatus, a quantity of an alcohol, such for example as

ethyl alcohol, is introduced into the still 1, and is distilled therein by means of the heat applied by the steam jacket 2. The alcohol vapors are conveyed away by the pipe 3 to 5 the preheater 4, where the vapors are heated to a temperature of between 250° and 350° C., but preferably of approximately 300° C., before they enter the catalyzer 5, the temperature at which it is desired to act upon 10 the alcohol vapors with the catalyzer. The alcohol vapors, therefore, enter the catalyzer 5 at the required temperature, so that the formation of acetaldehyde immediately begins as soon as the vapors reach the finely 15 divided metal carried upon the granular particles within the catalyzer tube 6. The oil jacket 7 maintains the vapors in the tube 6 at from 250° to 350° C., but preferably about 300° C., throughout the entire length 20 of said tube, and a large percentage of the alcohol vapors is thus decomposed to form acetaldehyde and hydrogen.

The vapors passing out of the catalyzer by means of the tube 10 are conducted 25 through the condenser 11, maintained at a temperature of 20-30° C., where any alcohol vapors present are condensed, and are collected in the receiver 14, from which the alcohol may be drawn off by means of the 30 pipe 15. The acetaldehyde and the hydrogen pass out of the receiver 14, and are conducted to the scrubbing tower or column 17, where the ascending vapors of acetaldehyde and hydrogen are subjected to a counter 35 current of an absorbing liquid, such as water, alcohol or acetic acid, preferably glacial acetic acid, by passing through the series of liquid sealed pans 18 therein, until substantially all of the acetaldehyde has been 40 come absorbed in the acetic acid and forms a solution, which passes out of the tower 17 by means of the pipe 20, and which com-

prises approximately one part of glacial acetic acid and one part of acetaldehyde.

The hydrogen passes away from the top of 45 the lower 17 by means of the pipe 23, from which the hydrogen may be collected in any suitable manner.

In the operation of this apparatus it is preferable to use acetic acid as the absorbing 50 medium, particularly when the acetaldehyde recovered is to be changed into acetic acid, as for example by the action of a current of air under pressure of 50-75 lbs. and at an elevated temperature of 45-65° C. 55

While we have described our invention above in detail, we wish it to be understood that many changes may be made therein without departing from the spirit of our invention. 60

We claim:

1. In combination, a catalyzer, means for passing alcohol vapors through the same to form an aldehyde and hydrogen an alcohol condenser, and means for separating the 65 resultant aldehyde and hydrogen comprising a scrubbing column for bringing acetic acid in contact therewith adapted to conduct the liquid and vapors into contact with each other on the counter-current principle. 70

2. In combination, a catalyzer, a still adapted to pass alcohol vapors through the same to form an aldehyde and hydrogen, an alcohol condenser, and means for separating the resultant aldehyde and hydrogen 75 comprising an apparatus for bringing an absorbing liquid in contact therewith.

In testimony that we claim the foregoing we have hereunto set our hands

ARTHUR A. BACKHAUS.
FRED B. ARENTZ.
